CLEANING IMPLEMENT

Louis Seewald, Amarillo, Tex.

Application October 23, 1945; Serial No. 623,922

4 Claims. (Cl. 15—209)

1

My invention relates to improvements in cleaning implements for use especially, but not necessarily, in cleaning toilet bowls and the like.

The invention is designed with the primary objects in view of providing an implement for cleaning toilet bowls easily and quickly without soiling the hands, and with a swabbing action, and a chemical agent whereby the bowls may be rendered sanitary after use.

Another object is to provide an implement of the character for the purposes above set forth and which embodies a swab particularly shaped and otherwise adapted for cleaning toilet bowls, and which forms a part of the implement detachable therefrom without handling the same and is adapted for disposal down the toilet bowl without clogging the same or the discharge line of said bowl.

Other and subordinate objects also comprehended by my invention, together with the precise nature of my improvements, and the manifold advantages thereof, will become readily apparent when the succeeding description and claims are read with reference to the drawings accompanying and forming part of this specification.

In said drawings—

Figure 1 is a view in plan of my improved cleaning implement in a preferred embodiment thereof.

Figure 2 is a view in front end elevation, drawn to an enlarged scale.

Figure 3 is a view in side elevation, drawn to an enlarged scale.

Figure 4 is a view in side elevation of the tongs, with the swab detached.

Figure 5 is a view in plan of the swab drawn to a further enlarged scale.

Figure 6 is a view in plan illustrating the manner in which the outer layer and the liner of the sack of the swab are arranged.

Figure 7 is a view in perspective of the pad detached.

Figure 8 is a similar view of the stiffener sheet of the sack, and

Figure 9 is a view in transverse section taken on the line 9—9 of Figure 5.

Reference being had to the drawings by numerals, my improved cleaning implement, as shown, comprises, as its basic elements, a pair of handling-forming tongs 1, and a swab 2.

The tongs 1 comprise a pair of arms 3 crossed, intermediate the ends thereof, pincers fashion, and pivoted together, as at 4. Rear end hand-grip loops 5 are provided on the arms 3 for

2

operating the same to swing the front ends thereof into and from clamping relation. The front ends of the arms 3 are provided with a pair of depending, jaw forming, loops 6 adapted, when said ends are moved into clamping relation, to assume parallel, side-by-side relation to grip the swab 2 therebetween in a manner presently described. The loops 6 are preferably formed by bending the arms 3 downwardly and rearwardly as at 7, and then forwardly as at 8. The loops 6 terminate in oblique, lateral stabilizing loops 9, the purpose of which will presently appear.

The swab 2 is of elongated, rectangular form in plan, with a transversely rounded bottom 10, a longitudinal, central, upstanding top flap 11, and top sides 12 inclining downwardly from said flap 11 to said bottom. As best shown in Figure 9, the swab 2 has the form of a stuffed sack. The sack is formed of an outer, elongated, rectangular layer, or sheet, of reticulated material and which is designated 13 and preferably formed of cotton netting, with a similar liner layer, or sheet, 14 preferably formed of absorbent tissue paper. The layer or sheet 14 is formed with a central rectangular opening 15 therein which exposes the outer layer, or sheet 13 therethrough. A pad 16 of rectangular form and loosely packed cotton with suitably located slits 17 therein to render the same readily flexible covers the opening 15. The pad 16 is of the requisite size to slightly overlap the edges of the opening 15, as shown in dotted lines in Figure 6. The top sides 12 of the swab 2 are reinforced and shaped by a stiffener layer, or sheet, 18, of stiff blotting paper bent, as at 19, along its median line into obtuse angled form and between which and the bottom 10 said pad 16 is confined so as to form a pocket 20 between said pad and said sheet 18 which is filled with a suitable chemical cleaning agent preferably of granular or powdered form and as represented at 21. The flap 11 is stuffed, as at 22, with cotton to provide bulging sides on said flap for facilitating gripping the same.

In forming the described swab, the outer and the liner layers, or sheets, 13, 14 are folded over the sides of the pad 16 and over the stiffener 18 so that the end edges thereof will align, and are stitched together along the side edges thereof, as at 23, 24, also at the end edges thereof, as at 25, and across the end portions thereof, as at 26, to form the flap 11. The chemical agent 21, and the cotton stuffing 22 may be introduced into the sack at any suitable time between stitching operations.

In using the described implement, the swab 2

is clamped between the loops 7, as shown in Figures 1, 2, and 3 with said loops gripping opposite sides of the flap 11, and the stabilizing loops 9 engaged with the top sides 12 to prevent the swab from turning laterally of the tongs 1. With the loops 7 thus engaging the flap 11, the tongs 1 may be used as a handle for manipulating the swab in a toilet bowl, not shown, with a scrubbing action, the stabilizing loops 9 providing for exerting pressure downwardly against the swab 2 by the tongs and in a manner to compress the swab 2 without impairing the usefulness thereof. By dipping the swab 2 in the water in said bowl, said swab may be saturated with the water which readily finds its way through the outer and the liner layers, or sheets, 13, 14, and through the pad 16 to the cleaning agent 21, thus dissolving said agent so that the same may be readily squeezed outwardly through the pad 16 and said layers or sheets 13, 14 for use as an aid in cleaning operations. When the cleaning operation is completed, the tongs 1 may be manipulated in a manner which will be understood, to cause the loops 7 to release the flap 11 and said swab may be disposed of by flushing the bowl in the usual manner. Obviously, when a swab 2 is thus disposed of, it may be replaced by a new one in the tongs 1. As will be appreciated, the reticulated outer layer, or sheet 13, and the absorbent liner layer, or sheet, 14 provide for ready passage of water into the swab 2 to the chemical agent 21, and the pad 16 lends itself readily to the passage of water therethrough, while at the same time preventing too much water from reaching the chemical agent. The outer layer, or sheet, 13 facilitates scrubbing and the lining layer, or sheet, 14 and the stiffener sheet 18 provide for sufficient rigidity in the swab 2 to prevent the same from flattening out to an extent impairing its usefulness. All of the component parts of the swab 2, as will be evident, may be compressed in the bowl to squeeze the water out of the same to compress the swab 2, after it has been used for a while so that it may be readily passed down out of the bowl by flushing without danger of clogging the flushing line.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. An implement of the class described for use with a swab including a central top flap, said implement comprising a handle forming pair of tongs having front ends adapted for gripping op-

posite sides of said flap, said front end comprising a pair of opposed depending clamping loops adapted for engagement with opposite sides of the flap, said loops terminating in lateral loops adapted for engaging the top of the swab upon opposite sides of said flap to stabilize the swab against turning relative to said clamping loops.

2. An implement of the class described comprising a handle, and a swab at one end of the handle including a sack embodying an outer layer of reticulated material and having a stiffener in the top thereof, and a liner layer of absorbent flexible material, having an opening therein at the bottom of the sack, said sack having therein absorbent padding one side of which covers said opening and a chemical cleaning agent of finely divided form in said sack between said padding and said stiffener.

3. An implement of the class described comprising a handle, and a swab at one end of the handle including a sack embodying an outer layer of reticulated material, and a liner layer of absorbent flexible material, said sack having therein absorbent padding and a chemical cleaning agent of finely divided form, and a flexible stiffening sheet in said sack backing the padding and chemical agent.

4. An implement of the class described comprising a handle, and a swab at one end of the handle including a sack embodying an outer layer of reticulated material, and a liner layer of absorbent flexible material, said sack having therein absorbent padding and a chemical cleaning agent of finely divided form, said liner layer having an opening therein and said padding directly engaging said outer layer through the opening to facilitate saturation of the padding by water by dipping the swab in water.
